UNITED STATES PATENT OFFICE

HARRY A. FOOHTHORAP, OF HARRISBURG, PENNSYLVANIA, ASSIGNOR TO ELLIOTT-FISHER COMPANY, OF NEW YORK, N. Y., A CORPORATION OF DELAWARE

MASTER WHEEL POSITIONING DEVICE

Application filed May 14, 1925. Serial No. 30,269.

This invention relates to denominational selecting mechanism for writing computing machines. The object of the invention is to provide in machines of this character a simple and effective form of mechanism whereby, when a zone of computation is reached, the denominational selection of the computing mechanism will be automatically effected in accordance with the denominational values of the digits being written or printed.

In the accompanying drawings, Figure 1 is a rear elevation of a portion of an Elliott-Fisher billing machine, equipped in accordance with my invention.

15 Figure 2 is a sectional elevation.

Figure 3 is a rear view of a portion of Figure 1 with certain of the parts occupying different positions.

Figure 4 is a detailed perspective view of 20 the primary selecting rack and its coupling device, and

Figure 5 is a detailed view of a portion of the carriage.

As the machine illustrated herein is a well-known form it will be sufficient to direct attention to the fact that it comprehends, generally, a line space frame 1 which moves longitudinally of a flat platen for line spacing and supporting a carriage 2, on which is mounted a key operating mechanism (not shown), which is advanced across the platen for letter spacing as words and numbers are printed on a work sheet spread out on the platen.

35 In addition to the usual adjunctive devices of a typewriter, of what is known as the flat platen type, this machine is provided on the frame 1, in rear of the carriage 2, with a register bar 3, on which is mounted one or 40 more column registers 4. These registers embody computing mechanism, including denominational members or number wheels 5, occupying denominational positions corresponding to the denominational positions of 45 a column or computing zone of the work sheet, to which the registers are appropriated.

In addition to the number wheels 5, the registers include registering wheels, carrying mechanism, resetting mechanism, and various other ancillary devices well known in the

art and not requiring specific illustration or description for the purposes of this disclosure.

The column registers are operated by a column actuator 6, carried by an actuator 55 shaft 7, mounted on and movable with the carriage 2 and operated from numeral keys through the medium of differential mechanism which effects the rotation of the actuator in proportion to the numerical value of 60 the particular key depressed. As the printing point of the machine and the actuator 6 both move with the carriage, it is clear that as denominational selection is effected in a given column of the work sheet, a corresponding denominational selection in the computing mechanism is effected. It follows that when a digit is printed on the work sheet in a given denominational position, as, for instance, units, tens, hundreds, etc., 70 the number wheel of corresponding denomination will be rotated to an extent corresponding to the value of the printed digit.

In addition to these column registers 4, which are intended ordinarily to compute 75 column totals, machines of this character are equipped also with what is known as a cross-footer or cross-footing register 8, usually located at the right hand end of the carriage and including a cross-footer actuator 9, denominational members 10, and the various ancillary mechanisms necessary to effect a computation upon the operation of the members or wheels 10, by a master wheel in a manner generally similar to the described 80 operation of the column registers. The cross-footer master wheel 9 is mounted on a squared shaft 11, driven from the shaft 7, through intermediate gearing 12 of reversible form, including a reversing gear 13, which is shiftable, to what is known as the add or subtract 85 positions in which the motion transmitted to the master wheel 9 will be in opposite directions to effect addition or subtraction in the cross-footer. This selection of the character of the computation to be effected by the cross-footer is accomplished by a mechanism which 90 includes a gear shifting lever 14, connected to a small bell crank lever 15, by a connecting rod 16. Normally, the parts are in position 95

100

to add, but when it is desired that the cross-footer shall subtract during the printing of numbers in a given zone, the column register appropriate to that zone is provided with a subtract cam 17, which, upon movement of the carriage to such zone, engages a roller 18 on the end of the bell crank 15, and swings the latter to shift the lever 14, and reverse the gearing 12, which drives the cross-footer actuator.

No claim is made in this application to the add and subtract selection just described. The present invention relates more particularly to means for controlling the selective movement of the cross-footer master wheel 9 across the register and back to normal position. The wheel 9 is provided with a grooved hub 19, engaged by a spanner 20, extending from the master wheel carriage 21, mounted to slide on guide rods 22, and having at its upper side a toothed rack 23. This rack engages a pinion 24, keyed to a shaft 25, and having a similar pinion 26 at its opposite end, and mounted in suitable bearings 27, carried by the frame of the cross-footer. Coiled upon the shaft 25 is a retracting spring 28, secured to one end of the shaft at 29 (see Figure 2), and at its opposite end to a lug 30 on one of the fixed bearings (see Figure 1). Normally, the spring 28 is under tension to hold the master wheel carriage 21, and master wheel in retracted position. The pinion 26 is meshed with a driving gear 31, of comparatively large diameter, rotatable on the stud shaft 32 projecting from the wall of the cross-footer 8. At a point diametrically opposite the gearing 26, the driving gear 21 meshes with the primary rack 32 of the cross-footer selecting mechanism, or master wheel advancing mechanism, said rack being slidable in suitable bearings and connected at its left-hand end by means of a bracket or arm 33, to a coupling rod 34. The rod 34 is also slidably mounted, as, for instance, in bearings 35 and the arm 33 extends through a slot 36 in the rear wall of the carriage to limit the end-wise movement of the coupling rod and consequently of the rack 32 and associated parts.

It may be noted, by referring to Figure 4, that the rack 32 and the arm 33 are adjustably connected and are retained in their adjusted positions by a set screw 37. At its rear end the coupling rod 34 is provided with a coupling hook or latch 38, adapted to engage a coupling lug or projection 39, extended downwardly from the base plate 40 of a column register. Usually these base plates are detachable from the registers and may be used independently thereof, since it may not be desired to obtain column totals of numbers printed in a given column or zone, and intended to be included in the computation effected by the cross-footer, otherwise expressed as the cross-footer register. The selecting mechanism

may therefore be employed either in conjunction with or independently of one or more column registers, the only operative requirement of the coupling lugs 39 being that they be located in fixed positions relative to which the carriage and cross-footer move. The coupling hook is pivoted to the rod 34, as shown in Figure 4, and is yieldingly held by a spring 41, which, however, upon the retraction of the carriage allows the hook to yield as it is cammed under any coupling lug 39 which may obstruct its retractile movement. This camming of the hook under the lug is facilitated by forming these two members with similar cam faces 42 and 43. Normally, the rack 32 is held in its extreme forward position on the carriage and the master wheel in its completely retracted position by the spring 28, but when, in the advance of the carriage to a column position predetermined by the location of the coupling lug 39 along the register bar 3, the coupling hook 38 engages the lug, the advance of the coupling rod 34 and rack 32 with the carriage will thus be arrested and any succeeding movement of the carriage will cause its advance relative to the now fixed rack 32. This advance of the carriage will cause the gear 31, advancing therewith, to rotate by reason of its engagement with the rack and it will in turn rotate the pinion 26, the shaft 25, and the pinion 24 to advance the rack 23, the master wheel carriage 21 and the cross-footer master wheel 9. This advance will be sufficient to present the master wheel 9 to successive denominational members of the cross-footer as the printing point of the machine moves to successive denominational positions of the column. To effect the uncoupling of the master wheel advancing mechanism from the fixed lug, a tripper 44 is mounted on the carriage in such position that as the computing zone is passed the tripper will be brought into contact with the cam face 43 of the coupling hook, and will cam the latter downward, whereupon its release will permit the instant retraction by the spring 38 of the master wheel and the master wheel advancing mechanism.

It is thought that from the foregoing the construction and operation of the illustrated embodiment of the invention will be clearly comprehended, but the right is expressly reserved to effect such changes and modifications thereof as may come fairly within the scope of the protection prayed.

What I claim is:

The combination with a travelling register, and a relatively shiftable master wheel, of a master wheel carriage embodying a carriage shifting rack adjacent the front of the register, a sliding rack on the register in the rear of and below the first rack, normally travelling with register and adapted to be arrested and released during travel of the latter, means operative upon arrest of the sec- 130

ond rack to advance the first rack and carriage and including, a gear meshing with the second rack, a shaft spanning said gear and first rack, gears on said shaft meshing with the first gear and rack, respectively, and of smaller diameter than said first gear, and a reactive motor adapted to be restored by such operation of said means to reverse the operation thereof and retract the carriage and racks to initial position and connected to said shaft for operation through the smaller gears thereby providing for the use of a light retracting motor to reduce resistance to the advancing operation.

In testimony whereof I hereunto affix my
signature.

HARRY A. FOOTHORAP.
